METHOD AND MEANS OF AIR CONDITIONING

Neal A. Pennington, Tucson, Ariz.

Application October 12, 1943, Serial No. 505,924

8 Claims. (Cl. 62—129)

1

This invention relates generally to the art of air conditioning. Specifically the invention is directed to the cooling and humidifying of warm, and relatively dry, outside air and directing it into the space which it is wished to air condition, such as rooms of homes, theatres, auditoriums, business places and the like.

The primary object of the invention is to provide an economical, compact air conditioning unit which will avoid the use of mechanical refrigerating units, outside water towers, or metallic heat exchange coils of any kind.

Another object of the invention is to produce a method and means of cooling and humidifying air wherein a preliminary contact cooling is provided by bringing the air into direct surface contact with a continuously exposed non-hygrosopic cooling medium without intervening metallic walls such as coils, plates or the like, and then further subjecting the air to evaporative cooling and humidifying by passing it through a continuously exposed film of water or the like; maintaining, in the meantime, desirable relations between the various factors determining a comfortable state of the air, viz: its dry bulb temperature, its wet bulb temperature, and its relative humidity, all determined solely by outside weather conditions and without the use of mechanical controls such as thermostats, humidists, and the like.

The advantages of the present invention will be most conspicuous in those geographic areas where the air to be conditioned generally possesses a lower humidity than is desirable. In such areas my improved method preliminarily cools the air without adding moisture (latent heat) and then, while still further cooling it adds to its moisture content in just the desired amount to produce the proper relative humidity, this being all accomplished at a minimum cost and with a minimum of moving parts.

The accomplishment of my objectives involves a two-stage operation. The first stage exists to cool the cooling medium to near the wet bulb temperature of the air to be conditioned prior to its surface exposure to such air; and the second stage exists to utilize such cooling medium, plus a water stream to properly treat the air to be conditioned, all in a manner and with the results as will fully appear by a perusal of the following detailed specification. The two stages are preferably incorporated in one compact unit or may be placed at separate points, where that practice might be found desirable.

In the drawings similar characters of reference refer to like parts in the several views:

2

Figure 1 is a diagrammatic outside elevation of a compact unification of the two stages of my improved apparatus.

Figure 2 is a vertical section of the same.

Figures 3, 4, 5, and 6 are cross sectional views of the unit taken respectively on the lines 3—3, 4—4, 5—5, and 6—6 of Fig. 2.

Figure 7 shows a modified form of the invention.

Figure 8 is a sectional view taken on a line 8—8 of Fig. 7.

Mechanism

Referring now more particularly to the characters of reference on the drawings, the numeral 1 designates a storage tank for the non-hygrosopic oil or other non-hygrosopic liquid, described more in detail under the description of operation, contained later in this specification.

The liquid is adapted to be withdrawn from the tank 1 through a pipe 2 by a pump 3 and is forced by said pump through a pipe 4 to two branches 5 and 6.

The branch 6 leads to and is adapted to discharge into a circular distributing trough 7 in the bottom of which are provided a plurality of holes 8.

Located immediately below the trough 7 and concentric therewith is a circular pad 9 made up of excelsior or other fibrous, spongy or foraminous material of sufficient porosity to readily allow the passage of air therethrough. Being positioned immediately below the trough 7, liquid from said trough may pass through the holes 8 and seep by gravity down through the pad 9 in a manner to cover the wall structure of the pad and keep the liquid in substantial surface exposure to any air which may pass through the pad.

The bottom of the pad 9 rests in a circular collecting trough 10 which receives the liquid which flows through the pad 9, and discharges it through a pipe 11 into a second circular distributing trough 12, the bottom of which is provided with a plurality of distributing holes 13. The branch pipe 5 is also arranged to discharge into the trough 12, the flow of liquid therethrough being controlled by a valve 5a.

Arranged underneath and concentric with the trough 12 is another circular pad 14 similar to the pad 9 so that liquid seeping through the holes 13 will flow by gravity through the pad 14 and be held in continuous surface exposure to any air passing through such pad.

The pad 14 rests in a collecting trough 15 which

has bottom holes 16 which will discharge liquid from the trough 15 into the reservoir 1.

17 is a water reservoir tank from which a pump 18 forces water through a pipe 19 to two branches 20 and 21. The branch 21 leads to a circular spray head 22, somewhat larger in diameter than, and arranged concentrically around, the upper distributing trough 7. A valve 21a controls the flow of liquid through the branch 21.

A circular pad 23 of similar composition to that of the pad 9 is disposed concentrically around the latter and beneath the water spray head 22 so that water discharging from the spray head will flow by gravity through the pad 23 and be held in continuous surface exposure to any air passing therethrough.

The bottom of the pad 23 rests in a water collecting trough 24, which has a plurality of discharge openings 25 which lead and discharge into a circular water distributing trough 26 arranged concentrically inside the inner periphery of the trough 12 and having a plurality of distributing holes 27. The branch 20 of the water pipe leads to a distributing head 28 disposed immediately below the trough 26.

A circular pad 29 of similar composition to that of the pad 23 is arranged concentrically inside of the pad 14 and immediately below the trough 26 and spray head 28 so that liquid discharged from either of these will flow by gravity through the pad 29 and be held therein in continuous surface exposure to any air passing through said pad.

The bottom of the pad 29 rests in a pan 30 from which openings 31 lead to a discharge trough 32.

Make-up water may be admitted to the tank 17 by a pipe 17a, the proper level in the tank being automatically controlled by a float valve 17b.

Both of the tanks 1 and 17 may be provided with suitable drains 1a and 17c, respectively, for cleaning purposes.

Within the air well A formed by the concentrically arranged pads 9 and 29, I provide a series of deflecting plates 33.

Preferably supported on the frame work of the unit is an air blower fan 34 driven by any suitable means, such as a belt 35 from a motor 36, which motor also drives the pump 3 through the medium of belt 37.

An air duct 38 leads from the fan 34 and completely surrounds and encloses the upper end of the well A so that air driven from the fan through the duct will be forced into said well. A part of this air will be deflected by the plates 33 to pass through the porous pads 9 and 23, and another part will be deflected to pass through the porous pads 29 and 14.

Surrounding the pads 9 and 23 is an enclosed casing 39 having a divider partition 40 on one side, and on the opposite side is provided an outlet duct 41 having divider plates 41a, the duct 41 leading to the space to be air conditioned.

Operation

In operation, an inherently non-hygroscopic fluid is supplied in suitable quantity to the tank 1. I use the term "non-hygroscopic fluid," for want of a better term, to designate a fluid which will not exchange moisture with the air with which it comes in contact. This non-hygroscopicity may be due either to the inherent non-hygroscopicity of the fluid employed (as in my first variant, now being described), or (as in my second variant, to be described hereinafter) may be

due to having the same vapor pressure as the air being treated although inherently hygroscopic. Preferably, although not necessarily so, this fluid would be a light grade of white mineral oil, particularly an oil refined from a naphthenic base oil found in some of the Western crudes in the United States. An example of such an oil is White Oil No. 3 U. S. P. or Standard CT-70 oil, both produced by the Standard Oil Company of California. This oil, particularly the CT-70, is inexpensive, has a low viscosity (about 30 centipoises at 65° F.), a good thermal conductivity, a good specific heat, and practically zero vapor pressure at the temperatures employed. It has a specific gravity a little less than water, and a very good penetration of wood and other fibers. It is odorless and non-toxic, highly resists oxidation and will not spoil or acquire an odor upon long exposure to air. Lastly, and of great importance, it is almost one hundred per cent non-hygroscopic, which is very essential to the successful carrying out of my improved method of air conditioning. The part that such a non-hygroscopic fluid plays in my novel method will appear as this description of operation is proceeded with.

This non-hygroscopic oil or other fluid is pumped from the tank 1 through the pipe 2 by the pump 3 and forced through pipe 4 to branches 5 and 6. That passing through the branch 6 is discharged into the distributing trough 7 and flows through the holes 8 into the pad 9. It then flows by gravity through such pad 9, and due to the composition of the latter is held in a state of very considerable surface exposure.

After the oil leaves the pad 9 it flows into the collecting trough 10 from which it flows through openings 11 into the second distributing trough 12 and passes through holes 13 into the pad 14. It then flows through this pad by gravity and is thus again held in a state of substantial surface exposure. As it leaves the pad 14 it is collected in the trough 15 and flows through the opening 16 back into the tank 1 ready to repeat the circuit just described. That portion of the oil allowed to flow through the branch 5, if any, is discharged directly into the trough 12 and there joins the flow of the oil from the pad 9.

The water from the tank 17 is forced by the pump 18 into the pipe 19 and thence to the branches 20 and 21. That portion flowing through the branch 21 reaches the spray head 22 and flows therefrom by gravity through the pad 23 where it is held in very substantial surface exposure. As it leaves the pad 23 the water collects in the trough 24 and discharges from there through the holes 25 into trough 26 and thence through holes 27 into pad 29. It flows through this pad by gravity and is again spread out into a state of substantial surface exposure. It leaves the pad 29 to collect in the pan 30, flowing thence through openings 31 to drain 32, whence it is carried to tank 17. Water from the branch 20 flows through sprinkler head 28 and joins with the water coming from pad 23 to flow through pad 29.

Air is forced by fan 34 through duct 38 into well A, where it is broken into two streams, one passing through pads 9 and 23 and thence to the space to be air conditioned; and the other through pads 29 and 14 to the atmosphere.

The pads are inclined toward the air streams in the ratio of about one inch per foot of height, or other suitable ratio, in order to overcome the tendency of the air to blow the liquid toward the

front of the pads at their ends and hence to assure better distribution of the liquids through the pads.

The flowing streams of non-hygrosopic oil and of water function to cool and humidify the air stream which flows to the space to be conditioned, as follows:

This air stream originates from the outside atmosphere, which is warm and relatively dry, and is forced by pressure of fan 34 to blow first through the pad 9, then through the pad 23, into the casing 38, and finally through duct 41 to the space to be conditioned.

The non-hygrosopic oil flowing through the pad 9 has been cooled in the manner described later. Therefore, as the air stream is diffused through pad 9 it comes into intimate heat but not moisture exchange relationship with such non-hygrosopic liquid. This causes the air to give up some of its sensible heat to the liquid, but without acquiring any additional moisture or latent heat in the process, and accordingly without having its dew point changed. Hence, in passing through the pad 9 this stream of air to be conditioned has its dry bulb temperature and wet bulb temperature lowered and loses a portion of its total heat.

This air as it leaves the pad 9 passes to and through the pad 23 where the water is flowing in a state of surface exposure. Here the air is brought into both heat and moisture exchange relationship with the water and is hence further cooled, evaporatively, and humidified, its wet bulb temperature remaining essentially constant.

The air thus cooled and humidified moves through casing 38 and duct 41 to the space to be air conditioned.

The portion of the water passing through needle valve 21a and pipe 21 to final passage through pad 23 is usually only a small portion of the total water circulated through the system and can be controlled to fit conditions by operation of such needle valve 21a.

As this water seeps down through the humidifying pad 23 and hence comes into contact with the air flowing through such pad, it has its temperature quickly lowered to, or very near, the wet bulb temperature of such air. This air has a lower wet bulb temperature than that of the warm dry outside air because it has just passed through the non-hygrosopic liquid in pad 9 and given up some of its sensible heat. It follows therefore that the water passing through pad 23 very quickly assumes a temperature lower than the wet bulb temperature of said outside air.

This cooled water then joins and mixes with the portion of water not passed through valve 21 at a point just above the pad 23, as previously described. This mixture at first has a temperature slightly lower than the temperature of the water coming directly from tank 17. However, because of its exposure to the warm dry outside air being pushed through the pad 23 by the fan 34, the water moving through such pad 23 very quickly assumes a temperature at or near the wet bulb temperature of such warm dry outside air, surrounding the whole apparatus, and at substantially the same temperature as the water in tank 17. Thus, it will be noted that the use of one divided and then rejoining water circuit, rather than two separate water circuits, results in not wasting the coolness which the water acquires in the upper pad 23. Also I save the cost of two water pumps. It would not, however, con-

stitute a departure from the essential portions of my invention to have two separate water circuits.

The air stream passing through the pad 23 in contact with the water therein is cooled by evaporation of such water to or near the wet bulb temperature of the outside atmosphere.

This air then passes across to and through the pad 14 through which the non-hygrosopic liquid from the pad 9 is flowing. Here this cool and saturated air picks up heat from the liquid which the latter had acquired from the stream of air passing through pad 9.

It will be evident, therefore, that as the second stream of air passes through pad 14 it has its sensible heat greatly reduced, i. e. its dry bulb temperature is reduced to near its original wet bulb temperature.

In passing through the pad 14 this air is brought into intimate contact with the warm non-hygrosopic liquid which has just left the pad 9 and absorbed heat during its passage through such pad. The air is then in heat but not moisture exchange relation with said liquid, and hence such air reduces the temperature of the non-hygrosopic liquid to near the original wet bulb temperature of the air to be treated, so that this fluid will function in removing heat from the first stream of air when the cycle of movement of the liquid again carries it through the pad 9. It should be noted, as already mentioned, that the first stream of air is further cooled by the evaporation of water in pad 23.

The above described cycles of operation, with the desired resultants, is made possible by the fact that in both the pads 9 and 14 the liquid employed is non-hygrosopic, i. e. it neither gives up or absorbs moisture from the air which comes in contact with it, but is in merely heat exchange relationship with the air, thus allowing the two-phase or dual operation whereby the same liquid moving in a continuous circuit or cycle is utilized to first cool the air to be conditioned and then, reversely, is itself cooled to condition it for functioning to again cool air to be conditioned.

I have found that the most satisfactory results may be obtained from this dual or two-phase operation by so setting up the apparatus that the second or cooling stream of air is greater than the first stream to be cooled. Just how much greater depends upon the mean summer wet bulb depression prevailing in the climate in the area in which it is intended to operate it, and upon the amount of lowering of the wet bulb temperature desired in the air to be cooled. All these factors can readily be calculated and applied to give the desired results.

The evaporative cooling, if any, and the humidifying of the air to be conditioned occurs solely in the pad 23, and these factors can be controlled by the setting of the needle valve 21a, which determines the amount of water allowed to pass through such pad 23. This is usually only a small portion of the total water circulated through the system.

While the stage of the apparatus for cooling and humidifying the air to be conditioned, and that of cooling the non-hygrosopic fluid, are here disclosed as united into one compact unit, it is obvious that they may be located at separate points if that should be found desirable.

The form of the unit here shown is circular. It could, however, be square or such other shape as may be selected without in any way affecting the mode of operation set forth.

In Figs. 7 and 8 I show a modified form of

the invention, wherein the same general principles are employed, but in which I may make use of a hygroscopic liquid as the cooling medium, but in which the concentration of the liquid is held to a point where it may be brought into heat but not moisture exchange with the air to be conditioned.

The concentration of this solution is not constant. At any time it merely has, or tends to have, that particular concentration which will give it a vapor pressure equal to the vapor pressure of the atmospheric air with which it is in contact at that particular instant. When the amount of moisture in the air changes and hence the vapor pressure of the air changes (as it will from day to day or even from hour to hour, under normal weather conditions), the concentration of the hygroscopic solution also automatically changes in such a way that its vapor pressure tends to assume a value equal to the current vapor pressure of said air. This has to be the case because if the atmospheric air becomes more moist, then the solution will no longer be balanced with it but will have a lower vapor pressure than that of said air, and hence will absorb moisture from it until the vapor pressures of the two are again equal. On the other hand, if the air changes in such a way as to become drier then the vapor pressure of the solution will be greater than that of the air. Hence water will evaporate from the solution into the air until the equilibrium of vapor pressure is restored. Thus, it can be said that at that time the solution is, in a sense, non-hygroscopic and useful as a cooling agent for the purposes of my invention. It will never be necessary to add water to the solution, except perhaps when first placing the solution in the apparatus, as the concentration thereof, which is variable, is constantly maintained at the proper value by the vapor pressure of the atmospheric air.

I will now describe in detail the modified structure used when a solution of the character described is employed in carrying out my improved method of cooling air.

Mechanism

The numeral 42 designates the solution tank in which is maintained a supply of hygroscopic liquid of such concentration that when cooled and brought into contact with the air to be conditioned it will be in heat but not moisture exchange relation with the latter.

From the tank 42 a pipe 43 leads to a pump 44 driven by any suitable means, such as a belt 45 from a motor 46. A pipe 47 leads from the pump 44 to a coil 48, the convolutions of which are embedded in a pad 49 of a structure such as that of the pad 14.

From the top of the coil 48 a pipe 50 leads to an annular trough 51 in the bottom of which is provided a pattern of holes 52.

Immediately below the trough 51 and arranged so that the holes 52 register therewith is a pad 53 of a construction similar to that of the pad 9. The bottom of the pad 53 rests in an annular pan 54 which has an outlet pipe 55 leading to and discharging into the tank 42.

The numeral 56 designates a water supply tank having a supply pipe 57, the supply being controlled by a float valve 58.

A suitable water pump 59 is provided, and leading from this pump is a pipe 60 having two branches 61 and 62, there being a control valve 63 in the branch 62. The branch 61 connects

with a spray coil 64 disposed atop the pad 49 and adapted to discharge onto the top of said pad so that the water may seep through the pad.

The branch 62 leads to and connects with a spray coil 65 disposed atop an annular pad 66 of a structure similar to the pad 23. This pad is concentric with the pad 53 and rests on the bottom of a housing 67 in the bottom of which are holes 68 which are immediately above the pad 49 so that water passing through the pad 66 will discharge through these holes 68 onto the pad 49. The pad 49 rests in a trough 56a having a drain 56b so that the water from pad 49 is collected in trough 56a and discharges through drain 56b into the tank 56.

The housing 67 forms an air chamber around the pads 53 and 66. It has a divider partition 69 on one side and an outlet duct 70 on the other side leading to the space to be air conditioned. Divider plates 71 are within the housing adjacent the duct 70. A portion 66a of the pad 66 is blanked off so that air will not pass directly from the pad into the duct 70 at that point. Pad 23 could be similarly blanked.

An air blower fan 72 is driven by a belt 73 from motor 46, and a duct 74 leads from the fan to the well W formed between the pads 53 and 49.

Operation

The operation of the pump 44 draws the liquid from the tank 42 and forces it through the coils 48 where it is cooled in the manner hereinafter described. The cooled liquid then passes through pipe 50 into trough 51, passes through holes 52 and seeps by gravity through pad 53. At the same time water from tank 56 is pumped through pipe 60 and branches 61 and 62 to spray heads 64 and 65 to flow by gravity through pads 66 and 49 in the manner previously described, and thence through trough 56a and drain 56b into tank 56.

The air to be conditioned is drawn from the atmosphere by the fan 72 and forced through the duct 74 into the well W. Here deflecting plates 75 divert a portion of the same to cause it to pass through the pad 53. Here it comes into direct contact with the liquid flowing through the pad. Although this liquid is hygroscopic in character it is, as stated, held at such a degree of concentration as to render it substantially non-hygroscopic. It is therefore maintained in heat but not moisture exchange relationship with the air passing through the pad 53. This causes the air to give up some of its sensible heat to the liquid, but without acquiring any additional moisture or latent heat in the process and without having its dew point changed. Hence, in passing through the pad 53 this stream of air to be conditioned has its wet bulb temperature lowered and loses a portion of its total heat.

As this air leaves the pad 53 it passes to and through the pad 66 through which the water is flowing in a state of substantial surface exposure. At this point the air is brought into both heat and moisture exchange relationship with the water and is hence further cooled, evaporatively, and humidified, its wet bulb temperature remaining essentially constant.

An even flow of the air through the pads 53 and 66 is effected by the deflectors 69 and 71 and the conditioned air passes into the housing 67 and hence through the duct 70 to the space to be conditioned.

The water passing through the pads 66 and 49 will be cooled in substantially the same manner as that passing through the pads 23 and 29 of

the other form of the invention previously described. Since the coil 48 is embedded within the pad 49 this cooling of the water around this coil operates to lower the temperature of the solution inside the coil to near the wet bulb temperature of the air to be treated prior to the solution reaching and flowing through the pad 53 so that at that point it is effective to lower the temperature of the air in the manner described.

The specific order of the steps of the method, and the apparatus selected and herein illustrated as preferred embodiments of my invention have been clearly set forth in connection with the foregoing detailed description of the invention. To those skilled in the art modifications of the specific structures and their application in carrying out the method of the invention will be evident from the detailed description of the specification. It is to be understood that the words which have been used are words of description rather than of limitation and that changes within the purview of the appended claims may be made without departing from the true scope and spirit of the invention in all of its aspects.

Having thus described my invention, what I claim as new and useful and desire to secure by Letters Patent is:

1. Apparatus for the conditioning of air comprising a pair of foraminous pads, means to pass a non-hygroscopic liquid through one pad, means to pass a stream of water through the other pad, means to pass a stream of air first through the pad containing the non-hygroscopic liquid and then through the pad containing the water, a casing enclosing said pads, a duct leading from the enclosure to the space to be air conditioned, another pair of concentric foraminous pads, means to flow water through one of said last named pads, means to flow said non-hygroscopic liquid through the other of said last named pads and thence to the first mentioned means, and means to flow air first through the water-containing pad and then through the pad containing the non-hygroscopic liquid.

2. Air conditioning apparatus comprising a first stage and a second stage, the first stage including two foraminous pads, means to flow a stream of water through one of said pads, means to flow a warm non-hygroscopic liquid through the other pad, means to pass air through the water-containing pad to evaporatively cool said air to a temperature lower than the non-hygroscopic liquid, means to then pass said cooled air through the other pad in contact with said non-hygroscopic liquid whereby to effect heat exchange relationship between the two and reduce the temperature of the liquid; the second stage comprising two foraminous pads, means to flow said cooled liquid through one of said pads in direct contact with the surface area thereof, means to flow a stream of water through the other pad in direct contact with the surface area thereof, means to flow a stream of air through the first pad of said second stage and in direct surface contact with the cooled liquid thereof and in heat exchange relationship therewith, whereby to reduce the temperature of said air, means to then pass said air through the second pad of said second stage and in direct contact with the water flowing through the latter whereby to effect further cooling of such air and to humidify the same, and means to then pass said air to the space to be air conditioned.

3. An air conditioning apparatus comprising a first stage and a second stage, the first stage in-

cluding a foraminous pad, means to flow a liquid through said pad out of direct contact with the surface area thereof, means to flow a stream of water through the pad in direct contact with the surface area thereof, means to flow a stream of air through the pad in direct contact with the water whereby to evaporatively cool the water and effect the lowering of the temperature of said liquid; the second stage comprising two foraminous pads, means to flow said cooled liquid through one of said pads in direct contact with the surface area thereof, means to flow a stream of water through the other pad in direct contact with the surface area thereof, means to flow a stream of air through the first pad of said second stage and in direct surface contact with the cooled liquid thereof and in heat exchange relationship therewith, whereby to reduce the temperature of said air, means to then pass said air through the second pad of said second stage and in direct contact with the water flowing through the latter whereby to effect further cooling of such air and to humidify the same, and means to then pass said air to the space to be air conditioned.

4. An air conditioning apparatus comprising two stages, each stage including two concentrically arranged foraminous pads, means to pass a non-hygroscopic liquid through the inner pad of the second stage and from there to the outer pad of the first stage and in direct contact with the surface area of both pads, means to pass a stream of water through the outer pad of the second stage and the inner pad of the first stage and in direct contact with the surface area of both pads, means to pass a stream of air first through the inner pad of the second stage and then through the outer pad of such stage, and in direct contact with the liquid and water respectively, and thence to the space to be air conditioned, and means to pass a stream of air first through the inner pad of the first stage and then through the outer pad of such stage in direct contact with the water and liquid respectively, and thence to the atmosphere.

5. That method of conditioning air which comprises establishing a zone of liquid which is inherently hygroscopic but is rendered effectively non-hygroscopic by being of such a concentration as to cause its vapor pressure to automatically come into equilibrium with the vapor pressure of the air with which it comes into contact, and which liquid is maintained at a temperature lower than that of the air to be conditioned and is held in a state of substantial surface exposure, passing the air to be conditioned into heat but not moisture exchange relationship with such liquid, and supplying such air to the space to be conditioned.

6. A method of conditioning warm dry air, which comprises: cooling a stream of air (of characteristics similar to those of the air to be treated) by bringing it into direct contact with a flowing stream of water; cooling a continuously circulating stream of non-hygroscopic liquid by bringing it into direct contact with said stream of air; bringing the air to be treated into direct contact with the thus cooled liquid; then increasing the moisture content of said last-mentioned air by bringing it into direct contact with a flowing stream of water; and then continuously directing said air into the space to be conditioned.

7. In an apparatus for the conditioning of air, the combination of: a heat exchanging but not moisture exchanging cooler, which cooler comprises

11

a foraminous pad and a stream of non-hygroscopic liquid circulating through the pad, such liquid being of lower temperature than the temperature of the air to be conditioned; a humidifier comprising a foraminous pad and a stream of water circulating through said last named pad; the liquid circuit and the water circuit being wholly distinct, and means to force the air to be conditioned first through the cooler and then through the humidifier.

8. In an apparatus for the conditioning of air, the combination of: a heat exchanging but not moisture exchanging cooler, which cooler comprises a foraminous pad and a stream of non-hygroscopic liquid circulating through the pad, such liquid being of lower temperature than the temperature of the air to be conditioned; a humidifier comprising a foraminous pad and a stream of water circulating through said last named pad; the liquid circuit and the water circuit being wholly distinct; means to force the air to be conditioned first through the cooler and then through the humidifier; a casing en- 15 20

12

closing said pads; and a duct leading from the enclosure to the space to be air conditioned.
